UNITED STATES PATENT OFFICE.

WILLIAM BALLARD JOHNSON, OF GRAND JUNCTION, COLORADO.

STOCKMAN'S STOVE.

Application filed July 13, 1926. Serial No. 122,260.

This invention relates to stoves and particularly to stoves which are intended for ready transportation and which are, therefore, compact, relatively light, and easily 5 handled.

The general object of the present invention is to construct a stove of this character of sheet metal and so form the stove that it will be particularly strong and will not 10 be liable to break or have its joints open.

Another object is to provide means for interlocking the metal sheets constituting the side, top and bottom walls of the stove so that the sheets will interlock with each 15 other without the necessity of using rivets.

Still another object is to provide corner irons which will protect the corners of the stove and prevent them from being dented in.

20 A further object is to provide a stove comprising an outer casing and an oven disposed within the casing and extending transversely the full width of the casing and stove from the top and bottom of the 25 casing and the rear wall thereof so as to permit the products of combustion from the fire box to pass around the oven if necessary and, in this connection, provide means whereby the products of combustion 30 may be caused either to pass around the oven or to pass more directly to the stack or flue and to this end to provide a damper shiftable into positions which will prevent or permit the circulation of the products 35 of combustion around the oven.

A still further object is to provide a stove of this kind with a removable fire box so that the fire box may be taken out and dumped when desired or the fire laid 40 therein without the necessity of reaching into the stove for this purpose.

Other objects have to do with the details of construction and arrangement of parts to appear more fully hereinafter.

45 My invention is illustrated in the accompanying drawings wherein:—

Figure 1 is a perspective view of a stove constructed in accordance with my invention;

50 Fig. 2 is a longitudinal vertical section through the stove.

Fig. 3 is a longitudinal horizontal section on the line 3—3 of Figure 2;

55 Fig. 4 is a transverse section on the line 4—4 of Figure 2;

Fig. 5 is a fragmentary section through

a corner of the stove on the line 5—5 of Figure 1;

Fig. 6 is a fragmentary perspective view 60 of the damper plate 34.

Referring to these drawings it will be seen that the stove is rectangular in form and consists of a body which, as illustrated, is made of a single sheet of metal formed to provide a top 10, a bottom 11, and two 65 opposite side walls 12, this single sheet of metal being joined along the line 13 in any suitable manner. It will be understood that while I have illustrated a single sheet of metal as forming the body of the stove, 70 it might be made of a plurality of sheets.

The top 10 of the stove is formed with the upwardly extending thimble 14, upon which a stack or flue may be mounted. The front end of the stove 15 and the rear end 75 16 are joined to the body of the stove by forming the forward and rear margins of the body with a returned bend 16, see Figure 5, which extends parallel to the body of the stove and then the material is bent 80 outward so as to form a relatively large corner bead 17 and the edge of this bead is brought against the metal of the front or back sheet, as illustrated in Figure 2.

Both the front and back sheets 15 and 16 85 have inwardly extending flanges 18 which extend inward against the outer face of the returned bend 16, as shown in Figure 5. Thus, the sheets or sections which form the completed casing of the stove are interlocked with each other and engaged without the necessity of any rivets. At the same time ribs are formed by the beads 17, these ribs extending across the stove at each end thereof and thus reinforcing and protecting 90 the joints between the top and bottom plates and the front and rear of the stove, as illustrated best in Figure 1. Corner pieces 19 are riveted or otherwise attached to the corners of the casing so as to protect 95 these corners from any deformation in handling the stove.

Disposed across the top of the casing and attached to this top and extending to the end walls is an angle iron 20. Disposed 105 rearward of this angle iron is the oven 21. This is also composed preferably of a single sheet of metal bent into rectangular form in cross section and has a length equal to the width of the casing. The walls of the oven are inwardly flanged at 22 at one end and engaged over an inwardly projecting flange 110

23 formed on one side wall of the stove and defining an opening to the oven. These flanges are riveted or otherwise engaged with the side walls of the casing and lie flat against these side walls. The oven, as shown in Figure 2, is spaced from the top and bottom walls and the rear of the oven is spaced from the rear wall of the casing and, of course, the front wall of the oven is spaced a considerable distance from the front wall of the casing so as to provide a space 24 for the fire box.

Attached to the front wall of the oven and extending transversely across the front thereof is a baffle plate 25 which is parallel to the front wall of the casing and shields the oven from the direct heat of the fire. The fire box may be permanently mounted within the stove 24 but as illustrated the fire box 26 is rectangular in cross section and is closed at one end and is adapted to be inserted into the space 24 through an opening 27 in the side wall. The open end of the fire box 26 is provided with a rectangular frame 28 which is slightly larger than the opening 27 and hinged to this frame is a door 29 which when turned upward, closes the opening 27 and is held closed by any suitable latch. The front wall of the fire box is perforated at 30 and the front wall of the casing is slotted at 31 and provided with a sliding damper 32. Air will pass in through this damper and pass through the perforations in the fire box and so gives sufficient air to the fire.

The opening of the oven is also closed by means of a door 33 hinged to the casing below the lower wall of the oven and this door is also provided with a suitable latch 40 whereby it may be held closed.

Operating over the top of the oven is a damper plate 34 which is angular in form so as to provide a portion which rests upon the upper wall of the oven, an upwardly inclined deflected portion 35, and a horizontal portion 36. The thimble 14 is disposed adjacent one corner of the stove and this damper plate when it is pushed forward, acts to prevent or nearly prevent the direct passage of the products of combustion upward through the flue and causes these products to pass downward and rearward in front of the oven and beneath the same and then upward at the rear end of the oven and out through the flue. When the damper plate is drawn rearward, however, it will permit the direct passage of the products of combustion up over the front of the oven and out through the flue

and the degree of draft may be controlled 60 by adjusting this damper plate so that the inclined portion 35 will extend more or less across the lower end of the flue.

The advantages of my improved stove are as follows:—The ends of the stove are 65 locked into the remainder of the body without rivets, bolts, or screws and this locking means reinforces the corners of the stove so that the stove is not liable to be deformed or otherwise injured in transportation or 70 handling. The round corners 19 bolted, riveted or otherwise attached to the stove give protection when the stove is being packed on animals or in cars and both when in use or set up. The sliding draft plate 75 32 when closed will entirely prevent fire dropping out of the stove which is an absolutely necessary feature when the stove is used for camping purposes. The heavy 80 angle iron 20 extending transversely beneath the top plate and almost immediately above the fire box keeps this top plate from warping. By having a removable fire box it is possible to remove the ashes without taking 85 down the stove pipe.

It will, of course, be obvious that the stove may be made of different weights of sheet metal and it will be seen that a stove constructed in accordance with my invention is very strong, compact, and particularly 90 adapted for transportation on animals or by a wagon or by an automobile.

I claim:—

1. In a sheet metal stove, two plates disposed at right angles to each other, one of said plates being refolded upon the body of the plate and then extended to form a bead, the other plate extending between the end of said refolded portion and the bead and then being flanged to fit against the refolded portion to thus interlock the two plates and form reinforcements at the junction of said plates.

2. A stove of the character described, comprising a sheet metal body, rectangular in cross section, and end plates closing the ends of said body, each end of the body being folded upon itself and being extended in the form of an arcuate bead, each of the end plates having flanges extending inward into said refolded portions and interlocking therewith, the beads having their outer edges engaged with the end plates and constituting reinforcements for the corners of 115 the body.

In testimony whereof I hereunto affix my signature.

WILLIAM BALLARD JOHNSON.
